UNITED STATES PATENT OFFICE

105,935

DESIGN FOR A CRIB

Roman B. Bukolt, Stevens Point, Wis.

Application May 29, 1937, Serial No. 69,616

Term of patent 7 years

To all whom it may concern:

Be it known that I, Roman B. Bukolt, a citizen of the United States, residing at Stevens Point, in the county of Portage and State of Wisconsin, have invented a new, original, and ornamental Design for Cribs, of which the following is a specification, reference being had to the accompanying drawing, forming part thereof.

The figure is a perspective view of a crib showing my new design.

The ornamentation shown on the inner surface of the head of the crib is duplicated on the inner surface of the foot, and that shown on the outer surface of the foot is duplicated on the outer surface of the head.

I claim:

The ornamental design for a crib as shown and described.

ROMAN B. BUKOLT.
